UNITED STATES PATENT OFFICE

JOHN M. WILLIAMS, JR., OF WOODBURY, NEW JERSEY

INTERNAL COMBUSTION ENGINE

Application filed February 7, 1930. Serial No. 426,490.

My invention relates to improvements in internal combustion engines.

In accordance with my invention, an internal combustion engine is provided which comprises cylinder construction having openings or passages providing respectively for fluid admission into and fluid exhaust from the cylinder, and a piston operable in the cylinder and provided with valve means received by and having a sliding fit in one of such openings or passages and operable during operating action of the piston in the cylinder to establish and cut off communication alternately between the opening or passage and the cylinder.

More particularly in accordance with my invention, an internal combustion engine is provided which comprises cylinder construction having openings or passages providing respectively for fluid admission into and fluid exhaust from the cylinder, and an inverted piston operable in the cylinder and having an upwardly directed flange portion received by and slidable within one of such openings or passages and operable to establish and cut off communication alternately between the cylinder and the opening or passage upon operation of the piston in the cylinder.

My invention resides in the improved construction for internal combustion engines hereinafter described and claimed.

For the purpose of illustrating my invention, several embodiments thereof are shown in the drawings, in which

Fig. 1 is a central vertical sectional view of an internal combustion engine embodying my invention;

Fig. 2 is a reduced sectional view, the section taken on the line 2—2 in Fig. 1;

Figs. 3 and 4 are views similar to Fig. 1, illustrating modified constructions embodying my invention;

Fig. 5 is a sectional view, the section taken on the line 5—5 in Fig. 3;

Fig. 6 is a fragmentary perspective view, partly broken away, illustrating a modification; and

Fig. 7 is a view similar to Fig. 4, illustrating a modification of the construction shown thereby.

In Fig. 1 is shown a two-cylinder, two-cycle internal combustion engine comprising the cylinder constructions 10 and 11 each having the openings or passages 12 and 13 providing respectively for fluid admission into and fluid exhaust from the cylinder 14, and a piston 15 operable in the cylinder and connected to the common crank shaft by the connecting rod 16. A portion 17 of each cylinder head is disposed substantially centrally with respect to and spaced from the cylinder wall 18 to provide the annular space or passage 19 communicating at its upper end with the exhaust opening or passage 13.

The piston 15 in each cylinder is inverted, the upwardly directed cylindrical flange portion 20 received by and having a sliding fit in the annular passage 19 and constituting valve means or a valve member operable to establish and cut off communication alternately between cylinder 14 and the lower end of passage 19. For this purpose, the flange 20 is provided with the circumferentially disposed passages 21 extending inwardly as shown from the free edge thereof.

The cycle of operation will now be explained, starting with piston 15 at the end of a working stroke and accordingly in the extreme crank-end position, as shown at the left in Fig. 1, at which time discharge of the spent gases will be taking place from the cylinder into the exhaust opening or passage 13 by way of passages 21, as indicated by the arrows. Concurrently with such action, a fresh explosive charge will, as indicated by the arrows, enter the cylinder from the crank-case 22 by way of the annular inlet passage or manifold 12 and circumferentially spaced openings 23 in flange 20 at the base thereof. During the first part of the upward stroke, the remainder of the spent gases are driven ahead of the incoming fresh charge, and expelled by way of passages 21 into the exhaust opening or passage 13, after which the piston will have moved upwardly to a position whereat openings 23 are out of registration with the complementary openings 24 in the cylinder wall, each of which is in direct communication with the cylinder 14.

munication with inlet passage 12. In such position of the piston, the passages 21 will be entirely above and beyond the lower edge of cylinder portion 17, and the solid portion 5 of the flange or valve member 20 will be received by and accordingly effective to close the lower end of the annular passage 19 and cut off communication between the same and the cylinder. During the remainder of the upward 10 stroke of the piston, the fresh explosive charge will be compressed. When the piston is in, or substantially in the extreme head-end position, as shown to the right in Fig. 1, the spark plug operates in the usual manner 15 to ignite the charge. The piston is then driven downwardly, on the power stroke. After downward movement of the piston through the greater part of such stroke, the solid portion of the flange or valve member 20 will 20 have been withdrawn from passage 19 to open the lower end thereof and again establish communication between the cylinder and exhaust opening 13 by way of passages 19 and 21. After further downward movement 25 of the piston, during which a substantial part of the spent gases will be exhausted, passages 23 will begin to register with the complementary passages 24 to permit admission into the cylinder, by way of passage 12, of a fresh explosive 30 charge compressed in the crankcase during the downward stroke of the piston, as will hereinafter appear. When the piston reaches its extreme crank-end position, as shown to the left in Fig. 1, the inlet and 35 exhaust ports will be wide open, and the fresh charge will be flowing into the cylinder under pressure, the spent gases being driven ahead of such charge and forced from the cylinder by way of ports 21. Such arrangement or manner of operation provides 40 a scavenging action. The cycle will now be completed.

As shown, the crank shaft may be built up in sections 26, 27 and 28 connected by T-headed bolts 29, adjacent sections having a male-and-female connection 30 with each other and fixed against relative rotary movement by suitable keys 31. Section 28 carries a flywheel 32, while section 26 provides a 45 connection with the load. The number of cylinder units may be increased by disconnecting section 26 of the crank shaft and interposing between the same and section 27 one or more sections, as desired, the new 50 section or sections being identical to section 27 and connected to adjacent sections in the same manner as the latter is connected to section 28.

Fuel is drawn into the crankcase 22 from 55 supply conduits 33 by way of the ports 34 in the crank shaft sections. The arrangement is such that when piston 15 has moved upwardly from the extreme crank-end position, as shown to the left in Fig. 1, to a position whereat ports 23 are out of registration

with ports 24 and the pressure in the crankcase is below that in the associated conduit 33, port 34 will begin to come into registration with the latter and will be in full registration with the same when the piston has moved a relatively short distance further. After the piston has passed beyond the extreme head-end position thereof, as shown to the right in Fig. 1, port 34 will be out of registration again with conduit 33, and the 70 fresh charge previously drawn into the crankcase during the upward stroke of the piston will be compressed therein. From the foregoing it will be seen that at the end of the power stroke of the piston, when ports 23 are partially or substantially fully in registration with ports 24, the fresh charge previously compressed in the crankcase will flow into the cylinder at a relatively high rate, and drive the remaining spent gases ahead 75 and out through ports or passages 21 with a pronounced scavenging action.

The piston 15 and the central portion 17 of the cylinder construction may be provided, respectively, with suitable piston 80 rings 35 and 36, as indicated.

In the construction shown in Fig. 1, the passages 21 are in the nature of circumferentially spaced slots cut in the upper edge portion of the flange or valve member 20, that is, the material of the flange between the inner and outer faces thereof and throughout the length of these passages, is entirely removed or cut away. In lieu of such construction, that shown in Fig. 6 may be used, 90 wherein the upper end portion of the passage 21a, corresponding to each of the passages 21 in Fig. 1, is formed within the outer or free edge portion of the flange or valve member 20, the outer wall 37 throughout the entire 95 length of the passage and the upper end portion 38 of the inner wall being left intact, as shown.

An important feature of the present improved construction resides in the disposition of the central cylindrical head portion 17, which extends into the cylinder bore a substantial distance beyond the upper edge of the inner cylindrical wall 18 of the cylinder, in overlapping relation with respect thereto for three hundred and sixty degrees around the cylinder. When the piston, therefore, has completed its compression stroke, as shown at the right in Fig. 1, and the compressed charge is ignited, both of the two 110 outside rings 35 just above the ports 23 are pressing against the cylindrical wall 18 of the cylinder for the entire three hundred and sixty degrees around the same. These rings are, accordingly, both effective to hold the tremendous pressure developed within the piston at this time, and prevent any appreciable escape of the gases, at this pressure 115 by way of ports 23 and upwardly between the piston and cylinder wall to the exhaust 120 125

passage 13. It has been determined in tests that this feature of my construction accounts for important advantages over engines of this general type proposed heretofore in the 5 way of a substantial increase in compression and a corresponding increase in efficiency.

The modification shown in Fig. 3 is substantially identical to the construction shown in Fig. 1, except that the ports 23b, 10 corresponding to ports 23 in Fig. 1, are a substantial distance above the base of piston 15, and are directed downwardly, as shown, so that the fresh charge entering the cylinder under pressure is directed, as indicated 15 by the arrows, away from the exhaust ports or passages 21b, corresponding to passages 21 in Fig. 1. In Fig. 3, the piston is shown as being in the extreme crank-end position. As shown more clearly in Fig. 5, ports 23b, 20 are sharply inclined so that the fresh charge enters the cylinder in a direction substantially tangential with respect to the inner cylindrical face of flange 20 whereby a swirling movement of the charge is induced, as indicated by the arrows in Fig. 5. Each of the 25 ports or passages 21b in Fig. 3 is formed or provided as is passage 21a in Fig. 6, except that the outer wall 37 at each port is removed.

30 In the modification shown in Fig. 4, the construction is substantially identical to that shown in Fig. 1, the arrangement of intake and exhaust ports, however, being reversed, that is, ports 21c, corresponding to exhaust 35 ports 21 in Fig. 1, are intake ports and admit the fresh charge into the cylinder from the supply passage 12c providing communication with the crankcase. The ports 23c, corresponding to inlet ports 23 in Fig. 1, are exhaust ports, and provide for discharge of the 40 spent gases into the exhaust passage or manifold 13c. In Fig. 4, the piston is shown in the extreme crank-end position, whereat the exhaust and inlet ports are fully open. After 45 the piston completes the first part of the upward stroke, the exhaust and intake ports will be closed, and the fresh charge will thereafter be compressed, until the piston reaches its extreme head-end position, at 50 which time the spark plug 25c operates in the usual manner to ignite the charge. After completion of the greater part of the following power stroke, the exhaust and inlet ports will again be opened to permit discharge of 55 the spent gases and admission into the cylinder of a fresh explosive charge, as indicated by the arrows.

In the modification shown in Fig. 7, the construction is similar to that shown in Fig. 60 4, the exhaust ports 23d, corresponding to exhaust ports 23c in Fig. 4, being, however, disposed a substantial distance above the base of the piston 15 and immediately below the inlet ports 21d, as shown. In Fig. 7 each of 65 the inlet ports 21d is formed or provided as

is the port 21a in Fig. 6 except that the upper end portion 38 of the inner wall is cut away. In Fig. 7 the piston is shown in the crank-end position thereof. The position of exhaust ports 23d is such that the same are fully 70 open before the piston, on the downward power stroke thereof, reaches the crank-end position. As the piston moves further on the power stroke the exhaust ports are carried beyond the lower edges of the complementary 75 exhaust openings 24d in the cylinder wall and are almost entirely below and out of registration therewith, as shown, when the piston reaches the crank-end position. This arrangement provides for an earlier opening 80 and a later closing of the exhaust ports, and, generally, for a greater and more effective exhaust period.

In the construction shown in Fig. 1, it is to be noted that during a certain period in the operating cycle there is a substantially straight-line, upward flow of the gases through the cylinder construction from the crankcase to the exhaust passage or manifold 13, as more clearly indicated by the arrows to the left in Fig. 1. More specifically, when the piston is passing through the crank-end position, the fresh charge previously compressed in the crankcase flows upwardly from the same into the interior of the cylindrical flange 20, during which time the spent gases flow upwardly and from the cylinder into exhaust manifold 13 by way of exhaust ports 21. Such straight-line, upward flow of the gases is interrupted when the piston has moved upwardly on the compression stroke to such position whereat the inlet and exhaust ports are closed, and just after substantially complete displacement of the spent gases by the upwardly flowing fresh charge. It is important to appreciate that the total effective exhaust-port area provided by ports 21 is relatively great whereby rapid exhaust of the spent gases, induced by the displacing 90 fresh charge, takes place. There is, therefore, a more complete cleansing or scavenging action than has been possible in constructions proposed heretofore.

The constructions shown in Figs. 3 and 7 have an important advantage over the others. This is attributed to the disposition of the ports 23b and 23d substantially at the mid-section of the piston flange 20. In each of these constructions, when the piston is at the end of the compression stroke and the spark gap operates to ignite the compressed charge, the only piston rings subjected at this time to the high pressure developed, are the two rings in the cylinder head portion 17. 115 With reference to the righthand cylinder in Fig. 1, however, it will be seen that during the same operating period in this construction, the two piston rings in the piston flange 20, just above ports 23, are subjected to the 120 125 130

high pressures, as well as the two opposite rings in the cylinder head portion 17.

Engines constructed in accordance with my invention may operate on the so-called Diesel cycle, in which case the spark plug may be omitted.

My present improved construction may be embodied in internal combustion engines for various purposes, such as outboard motors, 10 automobile and airplane motors, etc.

It is to be understood that my present improved construction is of broad adaptation, and may be embodied in constructions for internal combustion engines other than those 15 shown and described without departing from the spirit of my invention or the scope of the claims.

The invention claimed is:

1. An internal combustion engine comprising 20 an inverted piston and a cylinder therefor having passages for the admission of operating fluid into and the exhaust of spent gases from the cylinder, said cylinder provided with a central cylindrical head portion 25 having an outer cylindrical wall concentric with and spaced from the inner cylindrical wall of said cylinder, said head portion extending into the cylinder bore a substantial distance beyond the upper edge of said inner 30 cylindrical wall in overlapping relation with respect thereto for substantially three hundred and sixty degrees around the cylinder to provide an annular passage communicating 35 with one of said first-named passages, said piston having a sliding fit in said annular passage.

2. In an internal combustion engine, cylinder construction having a reentrant head portion spaced from the cylinder wall to 40 provide an annular passage, and an inverted piston having a flange slidable in said passage and provided at its free edge with a set of ports and at substantially its mid-section 45 with a second set of ports.

In witness whereof, I hereto affix my signature.

JOHN M. WILLIAMS, JR.
